UNITED STATES PATENT OFFICE.

ALFRED JOHNSON, OF SPOKANE, WASHINGTON.

HOT-AIR FURNACE.

Application filed January 25, 1924. Serial No. 688,454.

To all whom it may concern:

Be it known that I, ALFRED JOHNSON, a citizen of the United States, residing at Spokane, in the county of Spokane and State of Washington, have invented new and useful Improvements in Hot-Air Furnaces, of which the following is a specification.

This invention relates to improvements in hot air furnaces for heating purposes.

10 My improved furnace includes an outer shell or casing having a cold air intake and a hot air outlet with a fire box disposed in said casing, as is usual. In this class of furnaces, a flue is employed not only to convey 15 the products of combustion to the stack, but also to act as a heat radiator to heat the air in said casing. The function of heating this air has heretofore been very imperfectly performed and has resulted in a loss of a 20 material amount of heat units escaping through the stack.

Now it is a primary object of this invention to improve the heat radiating flue with a view of radiating substantially all the heat 25 units in the casing, and to this end, my invention, while residing in the aforesaid combination, has to do more particularly with an improved form of flue.

In accordance with my invention, the improved flue is arranged and constructed to not only retard the passage of the products of combustion toward the stack, as regards the speed of flow, but also, and as a result of such retardation, to more completely 35 radiate all the heat from said flue to the air inside of said casing.

A further feature consists in a disposition of the flue in such a manner that it will radiate heat not only to the upper air areas 40 but to all the air areas substantially throughout the height of said casing.

A further feature consists in disposing and arranging said flue in such a manner that in addition to radiating heat substantially 45 throughout the height of said casing, it will also radiate heat substantially throughout the horizontal breadth of said casing.

A primary feature of novelty consists in a flue for performing the functions set forth and which is a continuous flue, affording the products of combustion a single and circuitous path of flow, certain lengths of travel being constructed to retard, and certain lengths to facilitate the flow, these retarding and facilitating lengths being preferably alternately arranged.

My invention has other features which will be more fully described in connection with the accompanying drawings and which will be more particularly pointed out in and by the appended claims.

In the drawings:

Fig. 1, is a vertical longitudinal sectional view at line 1—1 of Figure 2.

Fig. 2, is a sectional view at line 2—2 of Fig. 1.

Fig. 3, is a sectional view at line 3—3 of Fig. 2, with the fire box in elevation.

Like characters of reference designate similar parts throughout the different figures of the drawings.

As shown, 1, 2, 3 and 4, designate the front, rear and side walls of the outer shell or casing of my improved hot air furnace. The structure of the shell may be of brick, 75 sheet iron or any desired type, this being immaterial to my invention. In the lower portion of wall 2, is a cold air inlet 5, and in the top 6, is a hot air outlet 7, which is shown provided with a pipe 8, adapted to 80 convey the hot air to the room to be heated. It will be obvious to anyone familiar with furnaces that by providing pipe 8, with the usual and well known cold air return, the device of my invention would function as a 85 pipeless furnace as well as a pipe furnace.

A fire box 9, is shown disposed in the casing and is very generally illustrated as the particular type of fire box is not important. However, in this form, it will be seen that the fire box extends longitudinally in the casing and its rear end is suitably supported at 10, the front end being supported by the front wall 1. A grate 11 divides the fire box into upper combustion and lower ash chambers 12 and 13, respectively. A door 14, affords access to the chamber 12, and a door 15, likewise affords access to the ash chamber 13.

Reference will next be made to the improved heat radiating flue, which in combination with the foregoing, constitutes my invention.

My improved flue has an intake end or section 16, which is connected in communication with the fire box at 17, preferably near the rear end thereof. This flue has an outlet end or section 18, which extends through the casing and is adapted for connection with a stack, not shown. The flue 110 has an intermediate heat radiating section which not only extends substantially

throughout the height but also substantially throughout the longitudinal area of the casting. Thus, it will be seen that by obtaining the widest possible distribution of the radiating area, and reducing the interior of the casing, substantially all of the air in the casing is bound to come into efficient heating contact with the radiating section of the flue as well as with the fire box. Further, I make the radiating section of the flue of a material of great heat conducting properties, such as thin sheet iron, whereby the greatest possible extent of heat radiation may be obtained.

15 In the specific form shown, I elevate the fire box to a relatively high position in the casing, and I form the intermediate flue section into a spiral coil of pipe which surrounds the fire box. The convolutions are indicated at 19, 20 and 21. It will be noted that the lower bights 22, 23 and 24, of the coils, have extensions 25, 26 and 27, which project outwardly through the casing wall 4, and which are provided with closures 28, 29 and 30. Thus it will be seen that these closures can be removed to permit the coils to be cleaned when they contain dust.

Now a special feature of novelty resides in a flue, as described, which is continuous, thereby providing a single circuitous path for the products of combustion through which all of the latter must pass before entering the stack. By means of a continuous flue, I obtain such a prolonged path of travel for the products of combustion, that I obtain practically all of the heat units therefrom. In actual practice, I have found that I can hold my hand against the outlet section 18, when the furnace is in full operation, thus proving that the radiating section coils fully radiate all the heat to the air in the casing. It will be noted that when the products of combustion are traversing a downward course through one of the downward lengths of the coils, there will be a resultant retardation of flow, and this retardation, in combination with the prolonged travel and the thin walls of the coils, results in the complete and efficient radiation into the casing.

50 Now in addition to the foregoing, it will be clear that the coils, which extend throughout the height of the casing and also substantially throughout the longitudinal areas thereof, present heat radiating areas to the incoming cold air at all elevations within the casing. Thus, the cold air is, or has heat applied thereto, from its entrance to its exit from the casing.

60 It will be noted that the casing is proportioned so that the fire box and the coils substantially fill the interior of said casing so that the air is forced to come into contact and be heated by the fire box and coils.

65 I provide supports 31, for supporting the

lower bights of the coils, and thereby, the coils themselves, and it will be noted that the coils are of such size and are supported in such a manner as to be free from contact with the fire box, whereby all the peripheries of the coils will thereby present radiating surfaces to the air.

In order to deflect the air against the coils, I provide deflectors 32 and 33, which extend from the walls of the casing toward 75 and preferably against the coils.

It is believed that my invention will be fully understood from the foregoing description, and while I have shown and described one specific form of my invention, I do not wish to be limited thereto except for such limitations as the claims may import.

I claim:

1. In a hot air furnace, an outer casing provided with a cold air inlet near the bottom thereof and a hot air outlet near the top thereof, a horizontal fire box disposed in said casing, and a heat radiating flue having an intake end communicating with said fire box and an intermediate radiating section extending substantially throughout the height of said casing above and below the fire box and longitudinally in said casing to radiate heat substantially throughout the vertical and longitudinal areas of said casing, and said flue having an outlet section extending outwardly through said casing and toward the stack.

2. In a hot air furnace, a casing having a cold air intake and a hot air outlet, a horizontal fire box disposed in said casing, and a continuous flue having one end connected with said fire box and the other end extending through said casing, said flue having a thin heat radiating intermediate section disposed in vertical convolutions about said fire box, and means for deflecting the entering cold air toward said convolutions.

3. In a hot air furnace, a casing having a cold air intake and a hot air outlet, a substantially horizontally disposed fire box in said casing, and a continuous flue connected with said fire box and having an end extending through said casing, said flue having an intermediate section spirally convoluted 115 in vertically disposed coils about said fire box and the coils extending longitudinally thereof.

4. In a hot air furnace, a casing having a cold air intake and a hot air outlet, a horizontal fire box in said casing, a continuous flue having one end connected with said fire box and the other end extending through said casing, said flue having an intermediate section coiled about said fire box, the lower bights of each coil having a cleaning section extending outwardly through said casing and provided with closures.

5. In a hot air furnace, a casing having a cold air inlet and a hot air outlet, a hori-

zontal fire box disposed in said casing substantially mid-way of the height thereof, and a continuous flue having one end connected with the top of said fire box and the remaining end extending through said casing, said flue having an intermediate heat radiating section coiled about said fire box

in substantially vertically disposed convolutions, and means for supporting said convolutions free from contact with the fire 10 box.

In testimony that I claim the foregoing as my own, I hereby affix my signature.

ALFRED JOHNSON.
